FRANCIS A. DUGRO, OF NEW YORK, N. Y.

MEANS FOR ATTACHING BOMBS FROM FLYING-MACHINES TO OTHER OBJECTS.

1,146,695.

Specification of Letters Patent. Patented July 13, 1915.

Application filed May 19, 1915. Serial No. 29,100.

To all whom it may concern:

Be it known that I, FRANCIS A. DUGRO, a citizen of the United States, and a resident of the city of New York, borough of Manhattan, in the county and State of New York, have invented a new and Improved Means for Attaching Bombs from Flying-Machines to other Objects, of which the following is a full, clear, and exact description.

This invention relates to means for attaching bombs or other devices from flying machines to other objects, and in the application of invention as set forth herein it contemplates the attachment of a bomb to the periscope of a submarine from a flying machine passing thereover. I wish it to be understood, however, that the principal features of the invention are capable of application to many other uses, such, for instance, as the discharging or delivering of parcels or written messages either from one flying machine to the other or from a flying machine to any other object which may be projected into or adjacent the path of the machine.

More definitely stated, the invention contemplates primarily the equipment of a flying machine with means associated with a bomb or like explosive device, such means being extended far enough below the usual lines of the machine and having sufficient width or scope to make it feasible and practical for a portion of the downwardly projecting means to engage over the upper end of the periscope of a submarine either as it projects above the surface of the water or at any reasonable depth below the surface, such means engaging with the periscope serving to automatically free the bomb and the attaching means from the flying machine allowing the latter to continue in its course while the bomb will be in position to explode and destroy the submarine.

The foregoing and many other objects of the invention will hereinafter be more fully described and claimed and illustrated in the drawings forming a part of this specification in which like characters of reference indicate corresponding parts in all the views, and in which—

Figure 1 is a front elevation of a standard type of biplane equipped with my improve-

ment; Fig. 2 is a side elevation of parts of the device as seen from the line 2—2 of Fig. 1; Fig. 3 is a transverse sectional detail on the line 3—3 of Fig. 2; Fig. 4 is a diagram indicating the relation of the flying machine to the submarine just prior to the attachment of a bomb to the latter; and Fig. 5 is a modification of means for giving the bomb a rearward impulse at the time it is delivered from the aeroplane.

The several parts of this device may be made of any suitable materials, and the relative sizes and proportions of the same, as well as the general design of the mechanism may be varied to a considerable extent without departing from the spirit of the invention hereinafter more fully described and claimed.

At any convenient point along the lower portion of the frame 10 of a flying machine is secured a frame or casing 11 adapted to support one or more explosive devices or bombs 12 as upon a bottom or plate 13 shown herein as adapted to swing downwardly around the hinge 14 when a catch 15 is withdrawn releasing the bottom 13 from its normal horizontal position with respect to the casing 11.

At points 16 well spaced laterally from each other on opposite sides of the longitudinal center of the machine are rigid stationary brackets to each of which a joint 17 is pivoted on a horizontal axis 18 parallel to the direction of flight of the machine, and to the lower end of the joint 17 is pivoted a holder 19 upon a pivot 18' extending transversely of or at right angles to the pivot 18. The holder 19, as shown in Figs. 2 and 3, is preferably of tubular form and provided along its inner side with a slot 20 having an open bottom. Each of the holders 19 has a wire or other similar connection 21 leading from the lower end thereof laterally and upwardly to the frame of the machine either at its end or at some other point outwardly from the holder, said connection serving to normally resist any tendency of the holder to swing inwardly toward the longitudinal center of the machine around the pivot 18. Any suitable resilient means, such as a spring 23, may coöperate with the joint 17 or other part of the holder mecha-

nism to resiliently resist the tendency of the holder to swing rearwardly under normal conditions. In other words, the holder is adapted to swing in practically any direction when excessive strain is brought upon it and it is normally resisted from such swinging movement or held in a depending position by the connections above described. The guy wire 21 may have introduced there-
5 in a coil spring 24 to relieve any shock or strain which may be incident to a positive pull upon the holder inwardly, and it also may have a turn buckle 25 for adjusting or varying the degree of tension thereof for
10 ordinary purposes.

The foregoing specific description of each holder 19 and its connections will be understood as being applicable to both of them.

Any suitable means as, for instance, a line 20 19*, may be provided to enable the aviator to control the position of the holders 19 and parts intended to be supported thereby. As indicated, for instance, in Fig. 4, the holders are shown as folded up into a substantially 25 horizontal plane beneath the body of the machine and are adapted to be released so as to swing into a pendent position whenever desired.

At 26 I show a rod or staff of any suitable 30 length carried normally by or within a holder 19 but adapted to be dropped or pulled therefrom in accordance with the scheme of the invention. As shown in Figs. 2 and 3, the upper end of each rod 26 is 35 fitted slidably in the hollow holder 19 and has a finger 27 projecting laterally therefrom through the slot 20. Said finger serves several important purposes, among which is to constitute a point of connection at 27' 40 for a chain 28 or an equivalent flexible connection leading inwardly to or toward the bomb. Another function of the finger 27 is to serve as means coöperating with a leaf spring 29 or its equivalent carried by the 45 upper end of the holder 19 to retain the rod within the holder under normal conditions but permitting the same to be withdrawn downwardly therefrom when intended. Another chain or equivalent flexible connection 50 30 leads from the point 31 at the lower end of the bar inwardly toward the central vertical plane of the machine or all the way across to the corresponding point of the other bar. The chains 28 and 30 are held 55 substantially parallel to each other by a vertical central connection 32 and they, together with the two parallel normally vertical bars 26, constitute a parallelogram of sufficient width and depth to span the upper 60 end of the periscope 33 of a submarine 34 with comparative facility while the machine is sailing through the air. Each of the chains 30 and 32 may be provided with a coil spring connection 35, if desired. The

term "chain" as used hereinafter will be 65 understood as being of broad enough interpretation to cover any suitable form of flexible connection whether wire, wire cable, or the like.

The catch 15 above referred to may be 70 provided with a line 36 leading over a direction pulley 37 carried upon a bracket 38 secured to the casing 11 or other suitable rigid or stationary part of the flying machine. The opposite end of the line 36 is preferably 75 connected then to one of the chains 28 at a point below or adjacent the casing 11. The upper end of the chain 32 is secured to the bomb 12 and the intermediate portion of the chain 32 may be connected rigidly or loosely 80 to the transverse chain 28 at the point 39.

The operation of the device may be briefly described as follows: With the flying machine equipped as described, the aviator upon sighting the periscope may sail toward 85 the same with the bars 26 depending, as indicated in Fig. 1, and thereby he will cause the noose formed by the bars and transverse chains to engage the periscope. Even though the lower portion of the noose may 90 engage the water, it will be maintained in engaging position by the action of the bars and springs coöperating with the holders 19. The contact between any part of the chain 95 30 and periscope will cause the noose to be pulled immediately downwardly from the holders 19, the springs 29 being practically only strong enough to carry the noose while the machine is in operation. It follows, therefore, that as the noose engages over the 10 periscope, the first effect following the detachment of the noose from the holders will be to cause the line 36 to release the catch 15 and allow the bottom or shelf 13 to swing downwardly under the weight of the 10 bomb which, being connected by the chain 32 to the noose, will immediately drop into 11 engaging position with respect to the submarine. By this time, the flying machine will have passed onward out of the way of danger.

Any suitable means may be provided either for automatic firing of the bomb or for the firing thereof under the immediate control of the aviator, depending upon the 11 individual conditions. Ordinarily it is important that the bomb may not be fired until it is released from the flying machine, and hence, as a suggestion of practical means for carrying out this feature of the invention, I show at 40 a fuse connected to the bomb and leading therefrom is a line 41 connected to the frame of the machine or other fixed point. As the bomb leaves the machine under the operation already set forth, it will automatically set up a pull upon the line 41 with the result that a time fuse of any suitable nature may be set in

operation so that after the lapse of a predetermined number of seconds the explosion will take place.

A series of grapples 42 of any suitable nature may be connected to the lower ends of the bars 26 or any of the chains so as to increase the likelihood of engagement of the noose with the object to be attacked or to which the device is to be attached.

10 That portion 32' of the chain 32 which is connected to the bomb is preferably extended up within the reach of the aviator and is made adjustable as to its length between the noose and the bomb, whereby the time 15 elapsing between the moment of engagement between the noose and the periscope and the time of contact between the bomb and the submarine may be varied, or, under certain conditions, it is desirable to regulate the 20 distance of the bomb at the time of its explosion from the periscope.

As indicated at 12^a, Fig. 2, the bomb may be acted upon by a spring of any suitable nature which is placed under sufficient compression and so held by the bomb while in normal position on the machine to give the bomb a pronounced rearward impulse at the time it is tripped from the aeroplane and whereby the shock or strain upon the noose 30 incident to the inertia of the bomb will be counteracted. The shell 11 may be provided with a lug 11^a against which the opposite end of the bomb rests so as to maintain the spring under compression. When, however, 35 the catch 15 is pulled, the plate 13 drops away, setting the bomb free as above described. As an alternative means for giving the bomb an impulse, it may be carried within a casing 11^b in one end of which may 40 be carried a small charge of some explosive material 12^b adapted to be ignited or exploded by any suitable means for giving the bomb a rearward impulse for the purpose just described.

45 Any suitable means may be provided to safeguard the dropping downwardly of the rigid members 26 from the holders 19 during the maneuvering of the aeroplane or at such times when it is not intended for the noose and the bomb to be delivered. As an indication of suitable means for this purpose I show a pin 29^a which may be used in connection with either of the holders 19 and coöoperating with the flexible fingers 29 to 50 prevent them from allowing the pins 27 from downward displacement. A line 29^b may run from the pin 29^a within reach of the aviator so that when he wishes to prepare to throw the bomb, he may withdraw 55 the pins 29^a at which time the noose will be detachably supported upon the fingers. If found necessary or desirable, any suitable means may be provided in connection with the noose to grip or grapple upon the peri-

scope to prevent slipping of the noose therefrom.

I claim:—

1. The combination with a flying machine, of a temporary support for a bomb thereon, a laterally and downwardly projecting noose 70 connected to the bomb, and means to set free the temporary support to release the bomb when the noose is engaged over a relatively stationary object.

2. The combination with a flying machine, 75 of a pair of laterally spaced holders secured thereto, means to support a bomb upon the machine between the holders, a downwardly and laterally extending noose connected to the bomb, and means detachably securing the noose to said holders, substantially as set forth.

3. The combination with a flying machine and means carried thereby to support a bomb at approximately the longitudinal 85 center of the machine, of a pair of holders spaced laterally on opposite sides of said center, a pair of rigid members slidably supported upon and depending from the holders, chains extending inwardly from the 90 upper and lower ends of each rigid member toward the center aforesaid, means connecting the inner portions of the chains to the bomb, and temporary holding means for the rigid members allowing the same to separate 95 freely from the holders when a relatively stationary object is engaged thereby.

4. The combination with a flying machine, of means approximately in the central vertical plane thereof for holding a bomb, said 100 holding means including a plate adapted to move downwardly, a catch normally holding said plate in a horizontal holding position, a downwardly and laterally projecting noose below the machine, means connecting the noose to the bomb, and means extending between the noose and the catch to cause the catch to release and drop the bomb when the noose engages over a relatively stationary object.

110 5. The combination with a flying machine and means carried thereby to support the device to be delivered therefrom, of a pair of tubular holders connected at laterally spaced points on opposite sides of the center 115 of the machine, a pair of rigid members telescoped at their upper ends in said holders and detachably connected thereto, chains extending inwardly from each rigid member toward the other, means connecting said 120 chains with said device, means to cause the rigid members and said chains to be withdrawn from the holders when engaged over a relatively stationary object, and means to release said device from the machine immediately thereafter, allowing the machine to proceed on its way.

6. The combination with a flying machine

and a support carried thereby including a downwardly movable plate, of releasable means normally holding the plate in horizontal position to support a bomb thereon, a noose projecting downwardly and laterally with respect to said bomb support, means connected between the noose and the catch to release the same when the noose is engaged over a relatively stationary object whereby the bomb is allowed to drop from the plate, and means extending from the bomb to the machine to initiate the firing thereof as a result of the dropping thereof from the machine.

FRANCIS A. DUGRO.
